THREAD HEIGHT GAUGE

Charles H. Allen and Rosslyn C. Allen,
Pittsburgh, Pa.

Application August 7, 1940, Serial No. 351,744

1 Claim. (Cl. 33—199)

This invention relates to a gauge, and while primarily designed and intended for ascertaining and indicating variations in the heights or depths, from required standards, of screw threads in pipes, couplings, fittings, and the like, it will be obvious that the device may be employed for any other purposes wherein it is found to be applicable.

Important objects and advantages of the invention are to provide a gauge of the character described, which is self-centering and self-adjusting, which functions to automatically center itself in rounded top and bottom threads, which embodies an anvil with a shiftable guide sleeve that locates and holds the contact point exactly in the center of the root of a rounded bottom thread, which may be readily and conveniently engaged on the product to be measured or removed from the latter, which is simple in its construction and arrangement, durable, compact, attractive in appearance, positive in its action, and economical in its manufacture, operation and maintenance.

With the foregoing and other objects in view, which will appear as the description proceeds, the invention resides in the novel construction, combination and arrangement of parts herein specifically described and illustrated in the accompanying drawing, but it is to be understood that changes in the form, proportions, and details of construction may be resorted to that come within the scope of the claim hereunto appended.

In the drawing wherein like numerals of reference designate corresponding parts throughout the several views:

Figure 1 is a front elevational view of a thread height gauge constructed in accordance with the invention, and illustrating the application of the device to screw threads.

Figure 2 is a side elevational view of the anvil and associated parts embodied in the present invention.

Figure 3 is an enlarged front view, partly in cross section, of the anvil and of parts disposed within the latter.

Figure 4 is a side view of the guide sleeve.

Referring in detail to the drawing 1 denotes an anvil in its entirety. The anvil is an integral structure embodying an elongated, horizontally disposed seating block 2, a spacing shank 3 extending vertically upward from the seating block, and a connecting saddle 4 carried at the upper end of the shank. The seating block and the connecting saddle are illustrated as extending in

the same general directions, but it will here be noted that the anvil is also being constructed with the seating block disposed at right angles to the disposition of said connecting saddle.

5 The anvil 1 is provided with a comparatively large bore 5, which extends vertically through the seating block 2, through the spacing shank 3, and through the connecting saddle 4. The bore is open at both ends and the lower portion thereof is reduced as indicated at 6, to provide a seating shoulder 7 located within the seating block of the anvil structure.

10 A dial indicator 8, of any suitable conventional construction now in common use, is rigidly secured on the top of the anvil connecting saddle 4 by means of screws 9, or in any other suitable manner. The indicator has a dial displaying scale graduations, each of which latter represents one one-thousandth of an inch. The indicator includes a spring controlled actuating rod 10, and a fixed bearing for the latter indicated at 11. The bearing depends into the anvil bore 5, and the actuating rod projects beyond the lower free end of said bearing.

15 A most important feature of the invention resides in the provision and function of a guide sleeve 12, which is mounted for vertically shiftable movement in the anvil bore 5. The guide sleeve is formed with a comparatively large pocket portion 13, an intermediate guide portion 14, and a tapered lower portion 15.

20 The relative diameters of the pocket and guide portions 13 and 14, of the sleeve guide 12, provide a shoulder offset 16 between said portions 30 seating on the shoulder 7 formed in the wall of the anvil bore 5 in the manner hereinbefore set forth.

25 The pocket portion 13 is formed with a comparatively large pocket 17 to provide clearance 40 permitting the entrance of the lower end of the actuating rod 10 therein, during the operation of the device in the manner to be described.

30 A guide passage 18, opening into the pocket 17, extends vertically through the guide and tapered portions 14 and 15, of the guide sleeve 12. A contact pin 19 is shiftable extended through the passage 18, and has its upper end secured in the lower end of the actuating rod 10 by a screw thread connection, as shown, or in any other 45 suitable manner. The contact pin has a tapered contact point 19', which normally projects through and beyond the lower free end of the tapered portion 15 of the guide sleeve 12.

45 A spiral spring 20 is mounted in the anvil bore 5 and surrounds the projecting end of the actu-

ating rod 10 of the indicator 8. The upper end of the spring abuts against the lower end of the bearing 11, and the lower end thereof rests against the top edge of the guide sleeve 12, as clearly illustrated in Figure 3. The action of the spring normally maintains the sleeve offset 16 seated on the shoulder 7, whereby the tapered portion 15, of the guide sleeve 12, projects through the bore portion 6 and beyond the bottom face of the anvil seating block 2. The guide sleeve 12 is shiftable in the anvil bore, against the action of the spring, to fully retract the normally projecting tapered portion 15 thereof to within the anvil bore.

The seating block 2 of the anvil 1 is formed with tapered side walls 21, which latter converge downwardly to provide a rounded bottom 22 adapted for seating on the screw threads 23 of the work 24 to be gauged by use of the device.

As stated, the tapered portion 15, of the guide sleeve 12, is normally projected through the bore portion 6 and beyond the face of the rounded bottom 22 of the anvil 1 by the action of the spring 20. The contact point 19' of the contact pin 19 likewise is normally projected through the sleeve passage 18 and beyond the tapered outer end of said sleeve by the action of the spring controlled actuating rod 10 of the dial indicator 8. It will here be noted that the permitted movements of the guide sleeve 12 and of the contact pin 19 are entirely independent of each other, and that both said sleeve and contact pin may be repressed to retract same fully within the anvil structure. Prior to use, the indicator 8 is so calibrated that the permitted projection of the contact pin point 19' is such that when the latter rest properly on the bottom of adjacent threads of adjacent thread convolutions of proper heights, the dial indicator will register "zero." Any variations from the proper height or depth of the threads will obviously be registered by the indicator due to the retraction or projection of the contact pin to variations of the calibrated standard of the indicator.

In gauging threads, the seating block 2, of the anvil 1, is placed across the threads 23, as shown in Figure 1, and the whole gauge structure is positioned in radial alignment relatively to the axis of the work 24. Due to the rounded bottom 22, of the seating block, the proper positioning of the device on the work is conveniently and readily effected and greatly facilitated.

As herein stated, the important feature of the invention is the function of the guide sleeve 12. When the seating block 2 is placed across the threads, the tapered portion 15, of the sleeve 12, will automatically be forced, by the action of the spring 20, into the widest space between adjacent thread convolutions, and thereby centralizes the pin contact point 19' to locate and hold the latter exactly at the center of the root of the thread bottom that is being gauged by the device.

The present invention provides a most rigid and substantial instrument of its kind, which may be readily and conveniently used by a person of ordinary skill for accurately and efficiently measuring screw thread height and depth variations, even if the latter be so infinitesimal as to be incalculable by any other devices employed for analogous purposes.

What we claim is:

In a screw thread gauge of the character described, the combination with an indicator including an actuating member, of an anvil provided with a bore secured to the indicator, a spring controlled guide sleeve shiftable seated in said bore, said sleeve having a tapered portion normally projecting beyond the bottom of said anvil, a contact element carried by said member and extending through said sleeve, the free end of said element normally projecting beyond the free end of said tapered portion of said sleeve.
